UNITED STATES PATENT OFFICE

WILBUR G. PARRISH, OF CHICAGO, ILLINOIS

VENDING MACHINE

Application filed August 6, 1930. Serial No. 473,416.

My invention relates to vending machines, and more particularly to that class of vending machines in which a belt conveyor is employed to carry the articles to the point of discharge, and my main object is to provide a machine of this kind which is adaptable to commodities of different classes without material change.

A further object of the invention is to design the novel machine with adjustable means adaptable to articles of different heights, widths and depths.

A still further object of the invention is to construct the novel machine on lines of compactness yet with a capacity for a maximum number of the articles to be vended.

A final but nevertheless important object of the invention is to build the same of the fewest number of parts consistent with the requirements of the machine, and to make these parts simple and durable.

With the above objects in view and any others that may suggest themselves from the specification and claims to follow, a better understanding of the invention may be had by reference to the accompanying drawings, in which—

Figure 1 is an elevation of the novel vending machine, showing for the sake of illustration but two article divisons, although the machine may be extended to include many more such divisions;

Fig. 2 is an enlarged vertical section of the machine showing one of the article divisions in elevation;

Figs. 3 and 4, are, respectively, cross sections on the lines 3—3 and 4—4 of Fig. 2; the conveyor at the right-hand portion of Fig. 4 being in plan;

Fig. 5 is a vertical section, partly in elevation, on the line 5—5 of Fig. 4;

Fig. 6 is a vertical section of a coin control, partly in elevation, taken on the line 6—6 of Fig. 4;

Fig. 7 is a plan section taken on the line 7—7 of Fig. 6;

Fig. 8 is a fragmental detail elevation view from the line 8—8 of Fig. 6;

Figs. 9 and 10, are, respectively, detail

sections taken on the lines 9—9 and 10—10 of Fig. 6;

Fig. 11 is a perspective view of an adjustable bearing detail;

Fig. 12 is a fragmental vertical section of 55 the conveyor belt; and

Fig. 13 is a group perspective view showing the application of shelves to the conveyor belt.

While vending machines have employed 60 conveyor belts for the support of the articles to be vended, and the transportation thereof to a point of discharge, it is significant that such vending machines were either limited to articles of one size or to a 65 small capacity of articles where the divisions therefor were adjustable to articles of different size. In my embodiment, I have not only provided for a maximum number 70 of articles along the belt irrespective of their size, but have also provided by simply adjusting the machine to convey articles of different depths and widths, these values being considered from the patron's position. A 75 versatile machine is thus provided which accomplishes the above mentioned objects and other objects developing in the following description to their fullest extent.

Referring specifically to the drawings, 20 denotes the cabinet for the novel vending machine, the same being made with frontal windows 21 in a horizontal series, and these windows representing the divisions for each row or series of articles vended. Thus, as suggested in Fig. 2, one may see through one window a row of one commodity, in the next window a row of another commodity, and so on. Below each window is a discharge aperture 20a for the articles vended, and at one side of each window is a coin apparatus 22 having a slot 22a near the top for the insertion of the coin, a slot 22b near the bottom for the discharge of an unused coin or slug, and a knob 23 in the region of the center which must be turned in order to operate 90 the coin apparatus.

Immediately behind each window 21 is a conveyor mechanism which generally comprises an endless belt 24, top and bottom 95 guide pulleys 25 and 26 for the same, and a 100

series of shelves 27 outstanding from the belt. As partly shown in Fig. 2, the commodity articles 28 are supported between the shelves, it being understood that the conveyor is fully loaded with these articles and that only a few of these have been shown as a matter of example. The conveyor operates in a plane from front to rear and its pulleys 25 and 26 are formed with toothed cores 25a and 26a for the meshing of a similar formation 24a on the internal surface of the belt 24. The pulleys are journaled on spindles 29 carried by bearings 30. These bearings are slidably mounted on bars 31 extended horizontally from front to rear. The upper bars 31 enter hanger rods 32 by way of slots 32b in the same, these rods receiving set screws 33 into their lower ends and directed against the bars 31. The slots are of sufficient height to permit the bars to be raised if desired by the advance of the screws 33. A similar installation applies to the lower bar 31, posts 32a being employed in the manner of the rods 32, and the slots being made similarly to those in said rods. Cross pins 34 are made near the ends of the bars 31 next inside the rods 32 and posts 32a to block the bars from longitudinal motion relative to the rods or posts. It will be evident that the expedient just described is for the stretching of the conveyor belt 24 to a taut degree, this being simply done by the advance of the set screw 33 (and 33a below) to separate the bars 31 and so procure the stretching of the belt. The rods 32 and posts 32a are preferably supported by being riveted with their outer ends into strips 35 and 35a, respectively, in dovetail fashion as shown in Fig. 2, the strips being secured to the top and bottom of the cabinet by screws 35b. An independent support is thus provided for each conveyor, and the same principle of installation will thus apply to cabinets of different widths, wherein a lesser or greater number of conveyors are installed.

The belt is intended to be propelled through a limited distance each time the knob 23 of a given vending unit is turned to a predetermined extent by the patron, the mode of transmitting this motion to the belt being related in a later section. The discharge opening 20a is made of a height and width for the passage of an article of maximum size consistent with the purpose of the machine, and when articles considerably less than this size are to be vended, I make use of a filler plate 36, vertically slidable in guides 37 (see Fig. 3) to limit the discharge opening in a vertical direction, the filler plate being slotted at 36a for the application of a set screw 37 from within the cabinet to secure the plate at any height desired. The filler plate thus limits the discharge passage to approximately the height of the article, so that unscrupulous persons may not have access to articles other than that which has been vended to a

previous patron. The filler plate is made with a short rearward bend 36b to serve as a continuation of the shelf at the bottom of the discharge passage, rendering the course of the vended article smooth.

It will be noted in Fig. 2 that an intermediate sprocket 38 is interposed and meshed between the belt runs at about the height of the discharge passage of the cabinet. This sprocket not only spaces the belt runs against collapse but provides a firm backing for the belt at the point of the article discharged; and by making the lower pulley sprocket 26a smaller than the sprocket 38 a break in the belt is created whereby to spread or deflect the shelf on which the article about to be discharged rests from the next upper shelf. This action as the shelf reaches the position even with the plate bend 36b operates to propel or advance the article 28 a sufficient distance that it may be grasped between the fingers and taken out, as suggested in Fig. 2. The sprocket 38 is formed with a spindle 39 (see Fig. 11) which is freely journaled in a bearing 40 having an inward flange 40a and an outwardly threaded stem 40b. As indicated in Fig. 2, the bearing 40 for each end of the sprocket is slidably disposed in the forked portion 41a of a bracket 41 which is secured by screws or other means 42 to the rear wall of the cabinet. The sprocket 38 is thus adjustable from front to rear between the fork 41a, and any adjustment thereof may be fixed by mounting a nut 43 on the stem 40b and tightening the same against the fork 100 with the effect of drawing the flange 40a up against the latter.

It will now be evident that by adjusting the bearings 30 of the belt conveyor along the bars 31 and adjusting the sprocket 38 accordingly, the conveyor may be moved bodily from front to rear, permitting articles of greater depth to be held between the shelves. The latter are made considerably narrower than the belt, as clearly shown in Fig. 4, the width of the shelves being suitable for the support of articles of shelf width or approaching the width of the conveyor belt. In this respect it is advisable to have lateral guides for the articles in order that they may not become dislodged from the shelves by the periodical operation of the belt. Such guides are shown in the form of wall plates 44 and 45, the wall plates 44 adjoining the shelves corresponding to the frontal belt run and the wall plates 45 serving similarly with relation to the rear shelves. The wall plates 44 and 45 are made with top and bottom bearings 46 slidable on rods 47 and 48, respectively. The rods 47 and 48 extend from front to rear and are spaced midway in order to be independently disposed. The rods are supported by being tapped at their outer ends to receive the screw shanks 49 of slide blocks 50 which are operable in horizontal channel

bars 51 mounted inside the front and rear walls of the cabinet at heights corresponding to the rods. Thus, it is possible to move a given rod laterally by simply unscrewing 5 the same slightly to loosen its outer end from the channel and permit the rod and block 50 to be moved as desired and again fixed by the screwing down of the rod against in-turned mouth flanges 51 of the channel bars. 10 This expedient permits any wall plate 44 or 45 to be moved laterally of the casing or in relation to a given row of shelves 27. Thus when a given width of articles for a conveyor unit is determined, the wall plates may be adjusted 15 to form lateral guides for the travel of the article in order to prevent the dislodgment of the same. It will now be apparent that the wall plates 44 and 45 may also be slid from front to rear by means of their bearings 46 and stationed at any desirable point by advancing set screws 52 carried by the bearings 46. This feature adapts the wall plates to the depth of the conveyor; and the wall plates 45 are made with inturned flanges 25 45a for each pair of plates (more clearly shown in Fig. 3) to serve as retainers for the articles on the rear run of shelves and keep them from falling off the shelves when the latter are spaced considerably from the 30 rear wall of the cabinet.

The shelves 27 are connected to the belt by a particular arrangement whereby to render them readily applicable or removable. The belt is preferably made of thick composition 35 or fabric and has embedded in it at the height intended for each shelf a horizontal metal bar 53. This bar is formed with two forwardly extended flanges 53a which project into cavities 24a of a width suitable for 40 the flanges. Each shelf 27, on the other hand, is formed with a pair of flanges 27a which are made with inward U-bends 27b to constitute clips. These clips are in registration with the projected flanges 53a of the belt bars 53 and are tensioned to frictionally engage these flanges when the shelf is moved to advance the clips into the cavities 24a. The shelves are thus simply and firmly connected to the belt and may be 45 moved or replaced with ease. The shelf supporting units 53, 53a are preferably spaced in close succession, in order that a large number of shelves may be provided for a commodity in a flat or short package; 50 yet, should it be desired to carry a commodity of greater height, it is an easy matter to remove alternate shelves as clearly shown in Fig. 12 to accommodate the new article. In fact, where an article of much 55 greater height is to be carried more shelves may be removed to create the necessary space while maintaining the equi-distant spacing of the shelves along the belt. This feature enables the machine to be adapted for articles of different heights on short notice and

without any radical change, inconvenience or expense; also, the equi-distant distribution of the articles eliminates waste space.

The coin apparatus 22 of the vending machine may be of any suitable construction, 70 but I have given special preference to one of my own design for the reason that it is of very small bulk, taking up but a slight amount of room in the cabinet, and it has few and simple parts. It will be noted particularly in Figs. 4, 5, and 6 that the coin apparatus involves generally a tall box 54 in the top of which is a coin chute 55 extending from the coin slot 22a, and in the bottom of which is a small drawer 56 for the accumulated coins. At one side of the coin chute 55, the box 54 contains a highly poised magnet 57, and the coin chute is cut away as indicated at 55a so that the insertion of a ferrous slug or counterfeit will cause the 80 same to be drawn laterally toward the magnet. Only the upper part of the slug will be within reach of the magnet, so that when the slug has once been deflected it will fall of its weight into the space alongside the 85 chute, in which a secondary chute 58 will lead the spurious coin down for discharge by way of the slot 22b. A good coin is indicated as dropped in the chute 55 in Fig. 6, and it will be seen that the chute is here 90 cut away at 55b somewhat below the top of the coin when the latter rests on a tumbler 59. This tumbler is yieldably suspended by springs 60 carried by the sides of the chute. The spindle 61 of the external knob 23 is 95 carried midway into the box 54 and is there interrupted to form an extension 61a which passes through the rear wall of the box and continues a considerable distance in the cabinet. The spindle sections 61 and 61a are 100 transversely slotted in registration as indicated at 61b, and when these sections are in a normal position, that is, before the control knob 23 is actuated, the slots 61b may be considered as vertical. Now, when the 105 coin has been dropped as shown in Fig. 6, the spring 60 of the tumbler 59 will be calculated to yield so far as to cause the weight of the coin to depress the tumbler 59 to partly fill the slots 61b as shown. The spindle 110 sections 61 and 61a are by this connection joined in a rotatable sense, so that they will act as one when the knob is turned.

Behind the box 54, the spindle section 61a receives a gear pinion 62 loosely mounted on a sleeve 62a which is adjustable by being keyed 62b along the spindle section and set at any position by set screws 63. One edge of the conveyor belt 24 is cut with gear teeth 24b and positioned opposite the pinion 62 to 115 mesh therewith. On the other side of the pinion 62, the sleeve 62a rigidly receives a ratchet pinion 64 with which a pawl 65 carried by the pinion 62 is engageable through the pressure of a spring 66. The box 54 also 120

has an extension plate 54a (see Figs. 6 and 7) in a rearward direction and formed with an inward bend 54b, the latter forming a bearing for the inner end portion of the spindle section 61a as clearly indicated in Fig. 4. The plate 54a is horizontally slotted 54d and carries behind the slot a tapped fixture 54c from which is pivoted a dog 67 which by gravity engages the toothed periphery of the pinion 62 as clearly shown in Fig. 8. It will be evident that the turning of the knob 23 when the spindle sections 61 and 61a are operatively connected will when done in a given direction operate through the influence 15 of the ratchet pinion 64 on the pawl 65 to rotate the gear pinion 62; and a reversal of this rotation will be impeded by the dog 67. The action just mentioned will by the meshing of the pinion 62 with the belt rack 24b 20 operate to move the belt a desired distance. The direction of operation of the parts just described is intended to harmonize whereby to cause the frontal run of the belt to descend the desired distance when the knob 23 is given 25 a partial turn accordingly, and to have no effect on the belt when the knob is turned in the opposite direction, since the ratchet pinion 64 will slip the pawl 65 and the dog 67 will check the pinion 62 from any motion 30 whatever in a reverse direction.

Considering the knob as operatively connected, with the belt, it must be recalled from a foregoing section that the distance of belt travel for each article to be vended was 35 intended to be varied with the spacing of the shelves suitable for the height of the particular class of article. Therefore, the extent to which the knob 23 is turned must be varied accordingly, and insofar as the spindle section 61 is concerned, this is done as indicated in Figs. 9 and 10. It is here seen that the spindle is drilled with a series of diametrical bores 61c in a single transverse plane, these bores being in proximity to a frontal wall of 45 the coin apparatus box 54. A pin 68 is fitted in one of these bores and has an external head 68a; and another pin 69 is fitted in a different bore and has a head 69a, being extended beyond the head to receive a spring 70 which 50 is lead to a pin 71 of the said front wall for attachment. Also, between the two heads 68a and 69a is stationed a lug 72 which projects from the front wall aforesaid. The spring 70 draws the pin 69 to be in normal 55 contact with the lug 72. However, when the knob 23 is turned to separate the pin 69 from the lug, then the pin 68 forms a turning limit for the knob when its head 68a meets the lug 72. It will now be apparent that should the 60 pin 68 be removed and pressed into a different bore of the spindle the extent of the rotary movement will be changed. The bores will be so spaced as to correspond with the multiple arrangement of the conveyor belt 65 shelves, so that a greater turn of the knob

will result in a corresponding divisional movement of the conveyor belt.

Relative to the spindle section 61a, it will be understood that the normal position of the spindle section 61 will place its slots 61b in a vertical plane; therefore, in order to have the slots 61b of the spindle section 61a in registration at the same time, an expedient must be used whereby to provide a fixed origin of rotation for the spindle section 61a. This expedient is similar to the one used for the spindle section 61 insofar as counterparts of the spindle bores 61c, pin 69, head 69a, lug 72, spring 70, and pin 71 are concerned. These counterparts are seen in Fig. 9 and apply to the spindle section 61a opposite the rear wall of the box 54; and they are marked with the suffix X to distinguish them from the same parts in Fig. 10. In this connection, it will be understood that no variable limit need be provided for the rotation of the spindle section 61a, as the previously described variable limit or the section 61 will control both spindle sections identically when they have once been joined by the tumbler 59.

It will be apparent that the elongated construction of the spindle section 61a permits the shifting of the pinion assembly 62 rearwardly or forwardly of the cabinet by the adjustment of the screws 63 whereby to adapt the said pinion to the position of the conveyor belt when the latter has been moved accordingly. In this connection, the plate 54a is made with the horizontal slot 54d for the application of a screw 67a to hold the bracket 54c of the dog 67. Thus, the assembly of the bracket and the dog will be adjustable horizontally in harmony with the position of the pinion 62.

It will be evident that I have provided a machine which is versatile relative to commodities of different sizes. Thus, the same machine is suitable when a change in the size of the commodity is made either in height, depth or width. It must be noted that the shelf divisions of the belt conveyor are not restricted to a measured fit of the article deposited therein. In fact the article may be perceptibly lower or narrower; or it may be square shaped or round, such as in the case of fruits, soaps and the like. My principle calls for the change in the spacing of the shelves where the articles either require a greater spacing or will fit a smaller one and thus makes for a greater capacity of the conveyor. In conclusion, it may be summarized that the important features of the novel vending machine are; 1. The bodily adjustment of the conveyor from front to rear to accommodate articles of different depths; 2. The lateral adjustment of the wall plates to guide articles of different widths; 3. The peculiar means of spacing and attaching the shelves to the belt; 4. The propulsion of the belt by having the same

geared on its side edge; 5. The provision of the intermediate gear for spacing the belt runs and holding the frontal belt run forward; 6. The adjustable discharge plate; 5 7. The elongation of the coin operating spindle suitable to the bodily shifting of the conveyor belt; and 8. The variable rotation limit of the hand control knob consistent with the divisional travel of the conveyor belt.

10 While I have illustrated and described the invention in the preferred embodiment, it will be evident that the same is capable of minor changes and refinements, and it is my intention to include such changes and refinements as coming within the spirit and scope of the appended claims.

I claim:

1. A vending machine comprising a cabinet having a wall formed with a discharge opening, an endless-belt conveyor unit having projecting shelves and operative to carry articles on the latter opposite the discharge opening, and means to adjust the conveyor unit from front to rear and vice-versa relative to the wall to accommodate articles of different depths.

2. A vending machine comprising a cabinet, an endless-belt conveyor unit having projecting shelves and operative to carry articles on the latter opposite a discharge opening in the front of the cabinet, vertically-spaced shafts, pulleys on the latter and forming upper and lower guides for the conveyor belt, horizontally recessed bearings carried by the shafts, bars extending from front to rear in the cabinet and slidably receiving the bearings, and supports from the ceiling and floor of the cabinet and connecting with the corresponding bars.

3. The structure of claim 1, a backing pulley inside the frontal conveyor belt run and substantially at the height of the discharge opening, journals for said pulley, supports for the journals, and means to adjust said pulley in conformity with the shifting adjustment of the conveyor unit.

4. A vending machine comprising a cabinet, and endless-belt conveyor unit having projecting shelves and operative to carry articles on the latter, the course of the conveyor being in a vertical plane, and wall plates alongside the shelves and forming side guards for the articles, and means to adjust said wall plates toward and from the sides of the shelves.

5. A vending machine comprising a cabinet, an endless-belt conveyor unit having projecting shelves and operative to carry articles on the latter, the course of the conveyor being in a vertical plane extending in the direction of the depth of the cabinet, wall plates alongside the frontal run of shelves, and wall plates along the rear run of shelves, means to shift the conveyor from front to rear and vice-versa in the cabinet to accom-

modate articles of different depths, and means to shift the wall plates in conformity with the movement of the shelf runs.

6. A vending machine comprising a cabinet, an endless-belt conveyor unit having projecting shelves and operative to carry articles on the latter, the course of the conveyor being in a vertical plane extending in the direction of the depth of the cabinet, wall plates alongside the frontal run of shelves, and wall plates along the rear run of shelves, means to shift the conveyor from front to rear and vice-versa in the cabinet to accommodate articles of different depths, and means to shift the wall plates in conformity with the movement of the shelf runs, said means comprising bearings carried by the wall plates, and horizontal supports extending from the front and rear cabinet walls, said supports slidably receiving the bearings.

7. A vending machine comprising a cabinet, an endless-belt conveyor unit having projecting shelves and operative to carry articles on the latter, the course of the conveyor being in a vertical plane extending in the direction of the depth of the cabinet, wall plates alongside the frontal run of shelves, and wall plates along the rear run of shelves, means to shift the conveyor from front to rear and vice-versa in the cabinet to accommodate articles of different depths, and means to shift the wall plates in conformity with the movement of the shelf runs, said means comprising bearings carried by the wall plates, horizontal rods extending from the front and rear cabinet walls, said rods slidably receiving the bearings, and set screws directed by way of the bearings to engage said rods.

8. A vending machine comprising a cabinet, an endless-belt conveyor unit having projecting shelves and operative to carry articles on the latter, the course of the conveyor being in a vertical plane extending in the direction of the depth of the cabinet, wall plates alongside the frontal run of shelves, wall plates along the rear run of shelves, supports for the wall plates, slide blocks carried by the supports, and horizontal ways carried by the front and rear cabinet walls and receiving said slide blocks.

9. A vending machine comprising a cabinet, an endless-belt conveyor unit having projecting shelves and operative to carry articles on the latter, the course of the conveyor being in a vertical plane extending in the direction of the depth of the cabinet, wall plates alongside the front run of shelves, wall plates along the rear run of shelves, rotatable rods carried by the wall plates and tapped in their outer ends, screws receivable in the latter and having slide block external heads, horizontal channels carried by the front and rear cabinet walls and receiving the slide blocks, and inturned flanges frontally of the channels and forming abutments for said ends when

the rods are screwed down, this action drawing up the screws to fix the wall plates at selected positions along the channels.

10. A vending machine comprising a cabinet, an endless-belt conveyor unit having projecting shelves and operative to carry articles on the latter, the course of the conveyor being in a vertical plane extending in the direction of the depth of the cabinet, wall plates alongside the front run of shelves, wall plates along the rear run of shelves, rotatable rods carried by the wall plates and tapped in their outer ends, screws receivable in the latter and having slide block external heads, horizontal channels carried by the front and rear cabinet walls and receiving the slide blocks, and inturned flanges frontally of the channels and forming abutments for said ends when the rods are screwed down, this action drawing up the screws to fix the wall plates at selected positions along the channels, said wall plates being extended with bearings for the disposal of said rods, and set screws directed by way of said bearings to engage the rods and fix the same when their rotary adjustment has been determined.

11. A vending machine comprising a cabinet, an endless-belt commodity conveyor in the latter, said conveyor having commodity units adjustably spaced along the belt to provide compartments of predetermined dimensions, a hand control, an element operable by the hand control to procure the movement of the belt, said hand control having adjustable means associated therewith for regulating the movement of the element to correspond to the predetermined dimensions of the commodity units along the belt.

In testimony whereof I affix my signature.
